UNITED STATES PATENT OFFICE.

MARTIN M. ENGELHARDT, OF NEW YORK, N. Y., ASSIGNOR TO L. BARTH & SON, A
PARTNERSHIP COMPOSED OF LEOPOLD BARTH AND HARRY BARTH.

DESIGN FOR A PLATE OR SIMILAR ARTICLE.

58,471.

Specification for Design.

Patented July 26, 1921.

Application filed September 25, 1919. Serial No. 326,401. Term of patent 14 years.

To all whom it may concern:

Be it known that I, MARTIN M. ENGELHARDT, a citizen of the United States, residing in the Bronx, city, county, and State of New York, have invented a new, original, and ornamental Design for Plates or Similar Articles, of which the following is a specification, reference being had to the accompanying drawing, forming part thereof.

The figure is a plan view of a plate, show-

ing my new design, used for plates and similar articles.

I claim:

The ornamental design for a plate or similar article, as shown.

MARTIN M. ENGELHARDT.

Witnesses:

EDWARD SHAW,
HENRY J. LUCKE.
